US00D826234S

(12) **United States Design Patent** (10) **Patent No.:** **US D826,234 S**
(45) **Date of Patent:** **** Aug. 21, 2018**

(54) **INDICIA SCANNER**

(71) Applicant: **Hand Held Products, Inc.**, Fort Mill, SC (US)

(72) Inventors: **Peng Zhou**, Suzhou (CN); **Timothy R. Fitch**, Syracuse, NY (US); **Hao Xu**, Suzhou (CN)

(73) Assignee: **Hand Held Products, Inc.**, Fort Mill, SC (US)

(**) Term: **15 Years**

(21) Appl. No.: **29/560,799**

(22) Filed: **Apr. 11, 2016**

(51) **LOC (11) Cl.** **14-02**

(52) **U.S. Cl.**

USPC **D14/428**

(57) **CLAIM**

The ornamental design for an indicia scanner, as shown and described.

DESCRIPTION

FIG. 1 is a first perspective view of an indicia scanner; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is second perspective view thereof; FIG. 9 is a third perspective view thereof; and, FIG. 10 is a fourth perspective view thereof. The broken lines shown in the drawings of the indicia scanner are for illustrative purposes only and form no part of the claimed design.

1 Claim, 10 Drawing Sheets
